UNITED STATES PATENT OFFICE.

JOHN R. PAYNE, OF FREEDOM, INDIANA, ASSIGNOR OF ONE-HALF TO
JOSEPH L. PAYNE, OF HARRISBURG, ILLINOIS.

WIRE-WORKING IMPLEMENT.

SPECIFICATION forming part of Letters Patent No. 793,090, dated June 27, 1905.

Application filed March 30, 1905. Serial No. 252,912.

To all whom it may concern:

Be it known that I, JOHN R. PAYNE, a citizen of the United States, residing at Freedom, in the county of Owen and State of Indiana, have invented a new and useful Wire-Working Implement, of which the following is a specification.

This invention relates to wire-working tools, and has for its object to provide certain new and useful improvements in such devices as to enable the convenient handling thereof, particularly in working upon wire fences, to stretch, splice, cut, and otherwise handle the runner-wires in a simple and efficient manner.

The invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a perspective view of an implement embodying the features of the present invention. Fig. 2 is an edge elevation of one end portion thereof.

Like characters of reference designate corresponding parts in both figures of the drawings.

The present implement includes a pair of handle members 1 and 2, which are intermediately pivoted, as at 3, so as to swing across one another in parallelism, the handle member 2 having its rear end projected beyond the member 1 and provided with a ring or link 4, loosely engaging a perforation in the end of the member. The member 1 extends a suitable distance in front of the member 2, and this extended portion is laterally enlarged, as at 5, throughout its length, with its rear end formed into a cam-shoulder 6, with which the front end 7 of the member 2 is designed to cooperate to form wire-clamping members or jaws. The jaw-terminal 7 of the member 2 is disposed obliquely across said member, and a prong or finger 8 projects slightly beyond

and overhangs the jaw-terminal 7 in co-operative relation with a similar prong or projection 9 upon the outer face of the shoulder 6. Shear-blades 10 and 11 are carried by the inner faces of the members 1 and 2 between the pivotal connection 3 and the shoulder 6, the projecting edges of the blades being sharpened and set obliquely across the device. A substantially L-shaped slot 12 intersects that face of the enlarged portion 5 which carries the prong or projection 9, and in the longitudinal branch of this slot is pivoted a wire-clamping cam 13, co-operating with the outer end of the slot to clamp a wire thereagainst, said cam being provided with a handle or finger-piece 14. The outer terminal of the enlargement 5 is rounded or beveled, as at 15, and bifurcated or forked to form a claw 16.

Among the many uses to which the present implement may be put will be mentioned the following: The claw 16 may be employed for drawing nails, tacks, &c. Either of the wire-clamping devices may be engaged with a runner-wire and the claw end of the implement applied to a post as a fulcrum and the device then used as a lever to stretch the wire. The adjacent ends of the broken wire may be engaged with the respective wire-clamping devices and then the implement turned around the wire as an axis, so as to intertwist the wires, and thereby connect the same. Where a wire is slack or loose between a pair of posts, the prongs or projections 8 and 9 may be engaged over the same and the implement then twisted in a plane substantially parallel with the wire, so as to twist a loop therein for taking up the looseness or slack. When stretching a wire with the device used as a lever, the ring or link 4 will be found useful for engagement by a rope or piece of wire to tie the adjacent end of the lever to a post, so as to hold the wire in its stretched condition while being secured to the fence-posts.

Having fully described the invention, what is claimed is—

1. An implement of the class described comprising a pair of pivotally-connected handle members one of which is projected beyond the other and has its projected portion later-

ally enlarged to form a shoulder coöperating with the inner end of the other handle member to produce a wire-clamp, the enlarged portion of the first-mentioned handle member being 5 provided with a substantially L-shaped slot intersecting one face and opposite edges thereof, and a pivotal wire-clamping member mounted in the longitudinal branch of the slot and working in coöperative relation with 10 the end wall of said branch at the transverse branch of the slot.

2. An implement of the class described comprising pivotally-connected handle members one of which is projected in front of the other 15 and laterally enlarged with the rear end of

the enlargement coöperating with the forward end of the other handle member to form a wire-clamp, and projections carried by the rear end portion of the enlargement and the forward end portion of the other handle member, said projections overhanging the joint between said other handle member and the enlargement to form wire-twisting elements. 20

In testimony that I claim the foregoing as my own I have hereto affixed my signature in 25 the presence of two witnesses.

JOHN R. PAYNE.
